UNITED STATES PATENT OFFICE.

MAHLON M. CARR, OF FOSTORIA, OHIO.

TORCH.

SPECIFICATION forming part of Letters Patent No. 688,929, dated December 17, 1901. .

Application filed June 17, 1901. Serial No. 64,886. (No model.)

To all whom it may concern:

Be it known that I, MAHLON M. CARR, a citizen of the United States, residing at Fostoria, in the county of Seneca and State of Ohio, 5 have invented a new and useful Torch, of which the following is a specification.

This invention relates to torches of that class embodying a shell or casing containing inflammable or illuminating material, and has 10 for its objects to arrange for conveniently igniting the torch without resorting to matches and to have the illuminating material normally protected against accidental ignition.

With these and other objects in view the 15 present invention consists in the combination and arrangement of parts, as will be herein-after more fully described, shown in the accompanying drawings, and particularly pointed out in the appended claim, it being understood 20 that changes in the form, proportion, size, and minor details may be made within the scope of the claim without departing from the spirit or sacrificing any of the advantages of the invention.

25 In the drawings, Figure 1 is a perspective view of a torch embodying the present invention. Fig. 2 is a central longitudinal sectional view thereof.

Like characters of reference designate corresponding parts in both figures of the drawings.

Referring to the drawings, 1 designates a tubular open-ended shell or casing, within the lower end of which is fitted a wooden plug 35 2 to form a bottom closure therefor and also for the support of a pointed pin 3, which is embedded in the outer end of the plug and is designed to be stuck into a support for holding the torch when ignited. Within the shell 40 or casing is a suitable quantity of illuminating material 4, and in the upper surface thereof there is embedded a frictionally ignitable plug or material 5, which projects slightly above the upper edge of the shell or casing.

For covering and protecting the open end

of the casing or shell and the plug 5 there is provided a tubular cap 6, which embraces the upper end of the shell and has its upper end closed by means of a wooden plug 7, that fits snugly within the cap and is provided with 50 an outer marginal enlargement 8, forming a shoulder to rest upon the upper edge of the cap.

In the outer end of the plug 7 there is provided a transverse groove, seat, or socket 9, 55 in which is seated a frictional substance or material 10, which is capable of igniting the material 5 when frictionally rubbed thereon. This material 10 is flush with the outer end of the cap or plug, so as to avoid projections, 60 which would soon become chipped off.

To ignite the torch the cap is removed and inverted, after which the frictional material 10 in the outer end of the cap is rubbed upon the projected upper end of the igniting material 5, thereby igniting the latter, which in turn ignites the illuminating material, and thereby the torch is ignited in a convenient and effective manner.

What is claimed is—

A torch, comprising a shell or casing, illuminating material therein, a frictionally ignitable material in engagement with the illuminating material and projected at the open end of the shell or casing, a cap removably fitted to the open end of the shell, a closure plug inserted in the outer end of the cap and provided in its outer end with a socket or recess, and a frictional material for igniting the ignitable material, said frictional material being seated within the socket and flush with the outer face of the plug.

In testimony that I claim the foregoing as my own I have hereto affixed my signature in the presence of two witnesses.

MAHLON M. CARR.
